CLOTHES HOOK

Robert W. Schier, Northfield, and Larry F. Odar, Northbrook, Ill., assignors to Krueger Metal Products, Inc., Green Bay, Wis., a corporation of Wisconsin

Filed Mar. 18, 1968, Ser. No. 11,030

Term of patent 14 years

Int. Cl. D6—01

U.S. Cl. D33—8

FIG. 1 is a view in perspective of a clothes hook embodying our new design.

FIG. 2 is a view of the clothes hook in front elevation.

FIG. 3 is a view of the clothes hook in side elevation.

FIG. 4 is a view thereof in rear elevation.

FIG. 5 is a view thereof in plan.

FIG. 6 is a bottom plan view thereof.

FIG. 7 is a view thereof in cross section on the line 7—7 of FIG. 3.

FIG. 8 is a view thereof in cross section on the line 8—8 of FIG. 3.

We claim:

The ornamental design for a clothes hook, as shown.
